UNITED STATES PATENT OFFICE.

JAMES R. FERGUSON AND JOHN FERGUSON, OF CHESTER, CONNECTICUT.

BILL-HOLDER.

SPECIFICATION forming part of Letters Patent No. 335,907, dated February 9, 1886.

Application filed May 20, 1885. Serial No. 166,187. (No model.)

To all whom it may concern:

Be it known that we, JAMES R. FERGUSON and JOHN FERGUSON, citizens of the United States, residing at Chester, in the county of 5 Middlesex and State of Connecticut, have invented certain new and useful Improvements in Devices for Holding Book-Leaves, Papers, Bills, &c.; and we do hereby declare that the following is a full, clear, and exact description 10 of the same, reference being had to the annexed drawings, making a part of this specification, and to the letters and figures of reference marked thereon.

Figure 1 of the drawings is a perspective view of our invention; Fig. 2, an under side perspective view showing our improvement applied as a paper-file or bill-holder, and Fig. 15 3 an edge view thereof.

The present invention has for its object to 20 provide a spring holding device or clamp that can be used for holding the leaves of books in place; also for filing away bills or papers, holding shoe-strings, and other articles in stores, and the various uses to which the ordinary spring-clip may be applied.

The invention therefore consists in a bracket 25 provided with cams at its ends, and a spring-clamp formed of wire and connected to the ends of the bracket, and operating in connection with the cams, as will be hereinafter described.

In the accompanying drawings, A represents the bracket, and B the clamp formed of 30 spring-wire. In the construction of this clamp we have shown it formed of a metal tube, as being more preferable, but it may be made of other material, and solid and flat or other shape, as found preferable. When not made hollow, the bracket should have a mortise or depression at its ends to receive the ends *a* of the wire clamp B, whereby the clamp is held in engagement with the bracket. Upon the ends of the bracket A are cams *b*, against which the inner side of the elbows *c*, 35 or at the point where the ends are bent at right angles, bear. The cams *b* will firmly hold the wire clamp B against the book-leaf, bill, or other article placed under it, and when the clamp is raised the bent end or elbow *c* 40 following the incline of the cam and bearing against it, the ends of the clamp will be forced out laterally, and when released the spring in the wire will cause the clamp to resume its normal position. If preferred, stops *d* may 45 be formed at the extremity of the cams to

prevent the bracket from being swung too far back.

In Fig. 1 we have shown the device as adapted to be fastened against a wall or other stationary object, and in Fig. 2 to be used as a bill or paper file, the invention being applicable to various uses, and either made ornamental or plain, to suit the taste of the purchasers. It will be noticed that the bracket A is swiveled or pivoted to the fastening device C, as 60 shown in Fig. 1, the object thereof being to allow the bracket to yield when used for holding the leaves down in place. The advantage of this is to allow the bracket to adapt itself to the form of the book when all or most all 65 of the leaves are on one side. Thus the bracket is capable of securely holding a single leaf as well as the remainder of leaves on the opposite side of the book, this being an important feature when our invention is applied as 70 a book-leaf holder.

We do not desire to confine our invention to any special means of pivoting the bracket. So long as it is capable of a yielding motion at either end it would come within the scope of 80 our invention, and therefore the means shown is only one in many that may be used with advantage.

Having now fully described our invention, what we claim as new, and desire to secure by 85 Letters Patent, is—

1. A device for holding book-leaves, bills, papers, and other articles, consisting of a suitable bracket adapted to be attached to a suitable support and having cams at its ends, and 90 a spring-wire clamp with ends bent to engage with the ends of the bracket and operating in connection with the cams, substantially as and for the purpose set forth.

2. A device for holding book-leaves, bills, 95 papers, and other articles, consisting of a pivoted bracket having cam ends, in combination with a spring-wire clamp engaging with the ends of the bracket and operating in connection with the cams, substantially as and for 100 the purpose specified.

In testimony that we claim the above we have hereunto subscribed our names in the presence of two witnesses.

JAMES R. FERGUSON.
JOHN FERGUSON.
